AUGUST VOESEL, OF MAGDEBURG, GERMANY, ASSIGNOR TO THE FIRM FRIED. KRUPP GRUSONWERK AKTIENGESELLSCHAFT, OF MAGDEBURG-BUCKAU, GERMANY

APPARATUS FOR GRINDING THE ROLLS OF ORE CRUSHING OR LIKE MILLS

Application filed March 29, 1929, Serial No. 350,988, and in Germany April 2, 1928.

This invention relates to apparatus for grinding the rolls of ore crushing or like mills wherein the grinding apparatus is mounted on the framework of the rolling mill itself. According to the invention the shaft of the grinding tool is arranged at right angles to the axis of the roll so that the front surface of the grinding tool is presented to the said roll and the driving motor together with the grinding tool are adapted to be moved both in a parallel and in a transverse direction to the axis of the roll. The said parallel movement of the grinding tool is preferably effected automatically by the rotation of the roll under treatment. The grinding tool may consist of a disc that carries on its working surface, easily interchangeable abrasive bodies. It is preferable to mount the grinding tool on the driving shaft so that it is axially displaceable thereon and to provide means for example, a spring or the like, whereby it may be held firmly in its working or operative position. A grinding device, according to the invention, has the advantage that notwithstanding the scant space available for the transverse and parallel feed of the grinding tool, it may be easily and effectively manipulated and such manipulation is not in any way hindered by the framework of the mill. A further advantage resides in the fact that the feed of the grinding tool parallel to the roll axis, may be effected by the roll to the ground, and that the grinding tool, even when the roll is out of truth, is always in contact with the roll, and is able, if necessary to give way or to yield to any obstruction.

In the accompanying drawings illustrating preferred embodiments of the invention:—

Figure 1 shows diagrammatically a front view of an ore crushing mill, the mounting of the driving motor of the grinding tool being shown in cross section,

Figure 2 is a longitudinal section through the head portion of the grinding tool mount on an enlarged scale,

Figure 3 shows the grinding tool in its working position on an enlarged scale, and

Figure 4 is a front view of a modified construction of the device.

Referring to Figures 1, 2 and 3 the roll train consists of the two rolls 1 and 2 between which the material, such as ore, is disintegrated or crushed. Adjacent the roll 1, the grinding wheel 3 is mounted on the shaft 5 driven by the electric motor 4 and arranged at right angles to the axis of the rolls 1 and 2. The grinding tool consists of the disc 3' (Figure 3) which, at its working surface is provided with abrasive bodies 3'', the latter being fixed or secured thereto in an easily interchangeable manner. The driving motor 4 is mounted movably, on a stationary support 6 positioned parallel to the roll, and, together with the grinding tool 3 may be moved along the support 6 by means of the operating spindle 7. This longitudinal displacement of the grinding tool is effected automatically by the rotation of the shaft 1' of the roll 1 by the power transmission means 19, 20. The transverse feed of the motor 4 and of the grinding tool 3 is effected in the usual manner by rotation of the hand-wheel 9 provided on the spindle 8.

The support 6 is preferably inclined to the horizontal and the grinding tool 3, even if the roll to be ground is out of truth, is arranged to remain in constant contact with the roll and is able to follow any irregularities in the roll. This is effected by mounting the tool 3 on a stub shaft 5' adapted, by means of the feather key 5'' to rotate with the motor shaft 5 and to be capable of axial movement relatively thereto. A compression spring 11 is arranged between the housing 10 (Figure 2) of the motor 4 and the disc 3' carrying the abrasive bodies 3'', which allows a yielding displacement of the disc 3' when the roll to be ground is out of truth or when it meets any slight obstruction, and which returns the disc 3' immediately into its working position when the obstruction or the like is passed. One end of the spring 11 is seated in a cup-shaped boss 12 of the motor housing 10 and its other end enters into a similarly shaped boss in the hood 18. The cylindrical wall 18' of the hood is guided in its longitudinal movement by the flange 17 engaging on the 100

cylindrical boss 13 of the housing 10. The movement of the hood 18 is limited by limiting nuts 15 which are screwed on the outer ends of the bolts 16 carried by the housing 10 and which pass through the flange 17 of the hood 18. The initial tension of the spring 11 may be adjusted by means of the adjusting ring 14 which is preferably designed as a nut threaded on the driving spindle 5'. A slide bed or support is also arranged adjacent and parallel to the roll 2, corresponding to the support 6 for the roll 1, but which has an inclination in the opposite sense to that of the support 6. The motor 4 with the grinding tool 3 may be arranged on this support when the roll 2 is to be ground.

In the modified construction shewn in Figure 4 the feed of the grinding tool, in a direction longitudinally of the roll 1, is effected in the following manner:—Projections or pins 21 or the like are arranged on the front end face of the roll 1 concentric with the axis of the roll and the free extremity 22 of the double lever 24, pivoted at 23, protrudes within the circular path of the pins. The other end 25 of the lever is provided with a pawl 26 which engages with the teeth of a ratchet wheel 27 mounted on the spindle 7. When the roll rotates in the direction denoted by the arrow *x* the lever 22 by engagement, for example, with the pin 21' is swung about its pivot 23 in the direction of the arrow *y*, whereby the toothed wheel 27 is rotated and thus the grinding tool is moved along its bed in a direction parallel to the axis of the roll. When the lever 22 ceases to contact with the pin 21' the former is returned to its original position (Figure 4) by means of the spring 28. Each of the pins 21, which may be of any desired number, in like manner effects, through the intermediary of the double lever a displacement or feed of the grinding device longitudinally of the rolls.

Instead of effecting such longitudinal feed by means of the rotation of the roll itself, it may be effected by any suitable driving arrangement such as for instance by means of a direct belt or chain drive. The relative position of the grinding tool to the roll may after the termination of an operation, be varied in any suitable manner instead of by means of the wheel 9 and the transverse feed screw 8 as shown. In order to obviate the necessity of reversing the direction of rotation of the spindle 7 when the grinding attachment is moved backwards, the spindle may be provided with cross or double threads and change-over members may be arranged on the longitudinal support and adapted to engage with one or other of the threads in the usual way so as to obtain an automatic reverse.

What I claim is:—

1. In an apparatus for grinding the rolls

of ore crushing and like mills the combination with a rotary grinding tool arranged at right angles to the roll under treatment, so that the front face of said tool is presented to the roll, of means for revolving the latter, spring actuated means for resiliently keeping in contact the grinding tool with the roll under treatment, a screw and nut drive adapted to move the grinding tool along the roll under treatment parallel to its axis and of feeding means cooperatively associated with the roll under treatment and with the screw and nut drive so as to periodically actuate the latter.

2. Grinding apparatus for the purpose set forth and having the features outlined in claim 1, in which the spring actuated means for resiliently keeping in contact the grinding tool with the roll under treatment comprise a rotary hollow main shaft, a spindle carrying the grinding tool and being telescopically displaceable within said hollow shaft, a hood loosely fitting over said spindle and being longitudinally displaceable relatively to the latter, a plurality of set screws adapted to limit the movement of said hood, and an adjusting ring in the form of a nut threaded on the driving spindle of the grinding tool, and being engaged by the said hood.

3. Grinding apparatus for the purpose set forth and having the features outlined in claim 1, in which the said feeding means comprise a plurality of studs projecting from one of the front faces of the roll under treatment, said pins being arranged in a concentric circle about the axis of said roll, a rocker arm projecting into the path of said pins and a feed gearing cooperatively associated with the rocker arm and the screw nut drive.

In testimony whereof the foregoing specification is signed at Berlin this 13th day of March, 1929.

AUGUST VOEGEL.
